US0D1051879S

(12) **United States Design Patent** (10) **Patent No.:** **US D1,051,879 S**
(45) **Date of Patent:** **** Nov. 19, 2024**

(54) **OUTER COVERING FOR EARBUD CASE**

(71) Applicant: **Speculative Product Design, LLC**, San Mateo, CA (US)

(72) Inventors: **Monica Elizabeth Wright**, Falls Church, VA (US); **Bryan Minh Vo**, San Francisco, CA (US); **Christopher William Ledesma**, San Francisco, CA (US); **Bryan Lee Hynecek**, Redwood City, CA (US); **Derrick Del Morral**, San Bruno, CA (US)

(73) Assignee: **Speculative Product Design, LLC**, San Mateo, CA (US)

(**) Term: **15 Years**

(21) Appl. No.: **29/827,340**

(22) Filed: **Feb. 18, 2022**

Related U.S. Application Data

(62) Division of application No. 29/711,009, filed on Oct. 28, 2019, now Pat. No. Des. 944,011.

(74) *Attorney, Agent, or Firm* — Lerner David LLP

(57) **CLAIM**

The ornamental design for an outer covering for earbud case, as shown and described.

DESCRIPTION

FIG. 1 is a front perspective view of an outer covering for earbud case according to a first embodiment of our design;

FIG. 2 is a bottom rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of an outer covering for earbud case according to a second embodiment of our design;

FIG. 10 is a bottom rear perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines shown in the drawings are for the purpose of illustrating environmental structure that forms no part of the claimed design. The dot-dash lines are boundary lines that form no part of the claimed design.

1 Claim, 12 Drawing Sheets
